UNITED STATES PATENT OFFICE.

ADOLF GANZENMÜLLER, OF NEW YORK, N. Y.

SCUTTLE-HOLE PROTECTOR.

SPECIFICATION forming part of Letters Patent No. 569,867, dated October 20, 1896.

Application filed July 11, 1896. Serial No. 598,802. (No model.)

To all whom it may concern:

Be it known that I, ADOLF GANZENMÜLLER, of New York city, in the county and State of New York, have invented a new and Improved 5 Scuttle-Hole Protector, of which the following is a full, clear, and exact description.

The object of my invention is to provide a protector applicable to roofs or other overhead structures at the scuttle-opening in said 10 structures, being used auxiliary to the ordinary scuttle; and a further object of the invention is to so construct the scuttle-protector that should the scuttle be removed from over the scuttle-hole the protector will effectually prevent access being gained from the roof 15 of the structure to the chamber or apartment beneath the scuttle-hole; and to provide means for expeditiously and conveniently opening the scuttle-hole to substantially its 20 full extent and locking the protector in its protecting position.

The invention consists in the novel construction and combination of the several parts, as will be hereinafter fully set forth, 25 and pointed out in the claims.

Reference is to be had to the accompanying drawings, forming a part of this specification, in which similar characters of reference indicate corresponding parts in all the figures.

30 Figure 1 is a vertical section through a portion of a roof containing a scuttle-hole, the scuttle, and the protector, the said section being taken practically on the line 1 1 of Fig. 2. Fig. 2 is a bottom plan view of the scuttle-protector closed; and Fig. 3 is a vertical section through the roof and scuttle-protector, the section being taken substantially on the line 3 3 of Fig. 1.

In carrying out the invention, A represents 40 a roof, B the scuttle-opening therein, and C the scuttle covering the said opening and located on the roof.

The protector consists of a frame 10 of substantially skeleton construction, comprising 45 a horizontal member and a flanged member at the outer margin of the horizontal member. The opening in the frame of the protector is sufficiently large to permit the passage of a person through the scuttle-hole and 50 is only of slightly less dimensions than the dimensions of the scuttle-hole. The opening

in the frame 10 is adapted to be closed by a door 11, having a hinged connection, preferably, with the under side of the horizontal member of the frame, and the said door is 55 arranged to drop downward, and when closed its free end, or the end that is to drop, is located in a rabbet or recess made in the under side of the frame, as clearly shown in Fig. 1.

The door may be held in its closed position 60 by any suitable form of locking devices, as, for example, bolts 12 may be mounted to slide upon the under face of the door at the edge opposite the hinges, and these bolts are made to enter keepers 13, secured to the under face 65 of the frame. Hangers 14 are likewise projected downward from the under face of the frame 10, adjacent to the keepers for the bolts, and each hanger contains a pulley 15. A cord or rope 16 is passed over both of these pulleys, which are near opposite sides of the frame, and the ends of the cord are secured to eyes 17, or their equivalents, attached to the door at the underside, preferably adjacent to the bolts. 75

Instead of the bolts latches may be used, being, as illustrated, of angular construction, the horizontal members of the latches sliding within guides 18, secured to the under face of the frame, and these horizontal members 80 of the latches are of sufficient length to extend over the edge of the door to an engagement with its under face. Each latch is pivotally connected with a lever 20, and the levers are fulcrumed upon hangers or brackets 85 21, projected downward from the frame. The latches are preferably placed one near each side of the frame, as shown in Fig. 3. In Fig. 1 the door is illustrated in dotted lines as partially dropped, and when the door 90 is opened it is drawn upward by pulling downward upon the rope or cord 16.

Having thus described my invention, I claim as new and desire to secure by Letters Patent—

1. A device for protecting scuttle-holes consisting of a frame, a door having a hinged connection with the frame, the said door being arranged to drop downward, locking devices for holding the door in a closed position against the frame, pulleys located on the under side of the said frame, and a cord 95 100

passing over said pulleys and having its ends attached to the under side of the door near its free end, as and for the purpose set forth.

2. A device for protecting scuttle-holes, the same consisting of a frame having an opening therein of predetermined size, a door hinged to the frame and arranged to close the said opening, the said door having a hinged connection with the said frame and arranged to drop downward, locking devices for holding the door in closed position against the frame, hangers projected downward from the under face of the frame near opposite sides thereof and each carrying a pulley and a cord 15 passing over the said pulleys, and having its ends attached to the free end of the door, as and for the purpose specified.

3. In a device for protecting scuttle-openings, a frame fitted to the scuttle-opening 20 and provided with a drop-door, means for raising the said door from a lower to an upper position, and locking devices consisting of latches fulcrumed upon the frame and arranged to pass beneath the drop end of the door, guides for the said latches, and levers 25

connected with the latches and extending below the said frame, as and for the purpose set forth.

4. A device for protecting scuttle-holes, consisting of a frame secured within the scuttle-opening and having an opening therein of predetermined size, the said frame comprising a horizontal member and a flanged member at the outer margin of the horizontal member, the said frame having a rabbet or 30 recess made in the under side thereof, a door having a hinged connection with the under side of the horizontal member of the frame, the said door being arranged to drop downward, the free end of the door when closed 35 entering the said rabbet in the under side of the frame, locking devices arranged to hold the door in closed position, and means connected with the said door for raising the same from the open to the closed position, as 40 and for the purpose set forth.

ADOLF GANZENMÜLLER.
